UNITED STATES PATENT OFFICE

NORMAN J. H. WOOD, OF MIAMI, FLORIDA

DISPENSING MECHANISM

Application filed August 23, 1928. Serial No. 301,556.

The present invention relates to improvements in dispensing devices and has reference more particularly to a dispensing mechanism adapted to be used in combination with a brush.

One of the important objects of the present invention is to provide a dispensing mechanism which includes a barrel within which is removably arranged a collapsible paste or liquid holding tube, said barrel being adapted for a hollow brush head to be detachably connected with one end of the barrel for communication with the discharge neck of the collapsible tube, additional means being provided at the other end of the barrel for collapsing the tube to extrude the paste or liquid therefrom, and through a brush head or the like so that a quantity of the paste or liquid will be delivered to a brush or the like.

A further object is to provide a dispensing mechanism of the above mentioned character that includes a screw threaded shaft that is journaled for rotation within the barrel, a rotatable cap being mounted on the rear end 25 of the barrel, an external ring gear being associated with the cap for cooperation with a pinion carried by the rear end of the screw threaded shaft whereby said shaft will be operated when the cap is turned, a follower 30 or tube collapsing member being arranged for longitudinal movement on the screw threaded shaft when the rotatable cap is actuated.

A further object is to provide a dispensing mechanism of the above mentioned character that may be adapted for use in combination with an attached toothbrush or a shaving brush as desired, the parts being so constructed as to permit the same to be readily and easily assembled and disassembled for cleaning purposes and to further facilitate the removal of an empty tube and the refilling of the barrel with a full paste or liquid containing tube whenever necessary.

A further object is to provide a dispensing mechanism of the above mentioned character which is simple in construction, inexpensive, strong and durable and further well adapted to the purposes for which it is designed.

Other objects and advantages will become

apparent during the course of the following description.

In the accompanying drawing, forming a part of this specification, and in which like numerals indicate like parts throughout the same;

Figure 1 is a side elevation of the dispensing mechanism embodying my invention showing the protective casing over a brush head,

Figure 2 is a similar view showing the casing removed, and a tooth brush associated with the device,

Figure 3 is a longitudinal sectional view through the barrel and a portion of the casing showing the relationship of the parts constituting the present invention,

Figure 4 is a sectional view taken approximately on the line 4-4 of Figure 3 looking in the direction of the arrows,

Figure 5 is a similar section looking in the same direction,

Figure 6 is a detail view of the screw threaded shaft and the supporting means therefor, and

Figure 7 is a longitudinal sectional view through the tooth brush.

In the drawings, wherein for the purpose of illustration is shown a preferred embodiment of my invention, the numeral 1 designates the cylindrical barrel that is open at its respective ends and within which is fitted the shell 2, the end of the shell extending beyond the ends of the barrel as more clearly shown in Figure 3.

An annular bead 3 is formed on the outer face of the shell at each end thereof. A pair of bearings 4 are arranged on the inner face of the shell 2 adjacent the respective ends thereof for receiving the longitudinally extending feed screw 5.

A pinion 6 is arranged on the rear end of the feed screw and this pinion projects beyond the rear end of the shell as suggested in Figures 3 and 6.

Any appropriate means is associated with the forwardmost bearing for securing the feed screw in position. The purpose of this feed screw will be presently described.

Fitted in a detachable manner on the for-

ward projecting end of the shell 2 is the conical shaped head 7, the same being formed with a central through bore, the forward portion of which is threaded as shown in Figure 3.

The head 7 is furthermore externally threaded as at 8 adjacent the larger inner end portion thereof, the head 7 being of conical formation. The rear edge of the conical shaped head 7 is adapted to abut the forward end of the barrel 1.

A knurled cap 9 is detachably and rotatably fitted on the rear end of the shell 2 and formed on the inner face of the central portion of the cap 9 is the external gear unit 10 that has meshing engagement with the pinion 6 carried by the rear end of the feed screw 5 for turning the feed screw when the cap 9 is actuated and this arrangement is more clearly illustrated in Figures 3 and 5 of the drawings.

A tooth brush, bath brush, shampoo brush, nail brush or shaving brush may be used in conjunction with the present invention and in the present instance, I have illustrated a tooth brush, the same including a hollow brush head 11 from which extends rearwardly the hollow shank 12, the bristles extending from the brush head being shown at 13.

The free end of the shank 12 is formed with an externally threaded portion 14 that has threaded engagement within the threaded portion of the bore formed in the head 7 to provide a detachable connection between the shank and the head 7 and a shoulder 15 is formed on the shank forwardly of the threaded portion 14 for limiting the rearward movement of the shank in the head 7.

A paste or liquid conducting channel 16 is formed in the brush head and shank and discharge orifices 17 provide a means whereby the liquid or paste will be discharged into the bristles 13 of the brush.

An internally threaded socket 18 is formed in the rear end of the shank 12 for receiving the threaded shank 19 of a collapsible paste or liquid receiving tube 20 of the conventional construction, said tube being disposed within the sleeve and the barrel as indicated in Figure 3.

In this manner, a direct communication will be afforded between the discharge neck of the paste tube and a brush or the like for supplying a paste or liquid thereto when the brush or the like is in use and furthermore when the tube 20 is collapsed or depressed.

The collapsing means includes a yoke 21 that is formed with an internally threaded transverse bore for engagement with the feed screw 5 and a transverse pin 22 extends between the free ends of the arms of the yoke and has loosely mounted thereon the roller 23, which roller engages with one side of the tube 20, the opposite side of said tube resting against the adjacent portion of the shell 2.

A cap or casing 24 is disposed over the

brush head when the device is not in use and the open end of the cap is internally threaded for engagement with the threaded portion 8 of the conical shaped head 7.

In use, the cap 24 is removed and by turning the knurled cap 9 in one direction, the gear 10 will rotate the pinion 6 whereby to actuate the feed screw 5 and this will result in the yoke 21 being moved forwardly within the barrel 1 at the same time, the roller 23 will compress or collapse the tube 20 so as to extrude a certain amount of the paste or liquid contents through the discharge neck 19 into the channel 16 and through the discharge orifices 17 into the brush or the like.

After the contents of the tube 20 have been emptied the cap 9 is rotated in the reverse direction whereby to retract the carriage and the tube collapsing roller to the rear end of the barrel and the empty tube is replaced by a full tube whereupon the device is again ready for use.

As heretofore stated, a dispensing mechanism of the above mentioned character can be readily and easily assembled or disassembled for cleaning purposes thereof and when the device is to be used for other purposes, a brush of the type similar to the tooth brush may be connected to the conical head.

Furthermore the provision of the casing for the brush promotes sanitation and furthermore protects the same when not in use.

A dispensing mechanism of the above mentioned character can be constructed at a very low cost and will furthermore be strong and durable and at all times positive and efficient in its operation.

While I have shown the preferred embodiment of my invention, it is to be understood that various changes in the size, shape and arrangement of parts may be resorted to without departing from the spirit of the invention and the scope of the appended claim.

Having thus described my invention, what I claim as new is:

In a dispensing device of the class described, a cylindrical barrel open at its respective ends, an open ended shell fitted in the barrel and having its ends extending beyond the respective ends of said barrel, a collapsible paste tube arranged within the shell, a dispensing head secured on the forward end of the shell for receiving the discharge neck of the tube, a feed screw journaled for rotation in the shell, bearings for the ends of the feed screw carried by the end portions of the shell, a yoke formed with a transverse threaded bore in the crown portion thereof for receiving the feed screw, a tube engaging roller supported between the ends of the arms of the yoke for cooperation with the adjacent side of the shell to collapse the tube and extrude the paste therefrom through the dispensing head, a pinion secured on the

5 rear end of the feed screw, a rotatable cap supported on the outer end of the shell, and a gear unit carried by the inner face of the cap for meshing engagement with the pinion to actuate the same and move the yoke along the feed screw.

In testimony whereof I affix my signature.
NORMAN J. H. WOOD.
